A CORPORATION OF OHIO.

DUMP-CAR.

1,364,349.

Specification of Letters Patent.

Patented Jan. 4, 1921.

Application filed January 21, 1919. Serial No. 272,266.

To all whom it may concern:

Be it known that we, WILLIAM L. BURNER and JAMES H. COTTON, citizens of the United States, residing at Columbus, in the county 5 of Franklin and State of Ohio, have invented certain new and useful Improvements in Dump-Cars, of which the following is a specification.

The invention relates to a door lock for 10 the swinging door provided on a dump car, and is especially adapted for use in a car having a body pivoted near the lower edge of one end thereof and adapted to swing about the pivot to effect a discharge of the 15 contents thereof. The lock is adapted for manipulation positively both upon opening and closing of the car door, and is arranged to permit a partial opening of the door and to maintain that position until the 20 operator desires to effect a more complete opening, the entire matter being in the discretion of the operator. Essentially the invention comprises a lock member, a supporting member therefor, a manipulating rod 25 and a lever associated with the opposite end of said rod for the purpose of giving the rod direction in its lock manipulating functions.

In the drawings which are hereto attached 30 and hereby made a part of this specification the figure shows a dump car in side elevation with the invention attached thereto, the dumped position of the body being indicated in dotted lines.

35 Referring to the drawing 1 is the under-frame of a car having the body 2 mounted thereon and pivoted at 3 to be tilted and dumped as indicated. 4 is the door pivoted at 5 to swing outwardly away from the end 40 of the car body when the dumping operation is taking place, and carrying thereon the striker bar 6; the hook member 7 is pivotally supported at 8 by the bar 9 pivotally depending at 10 on the end of the car body 45 and imparting to the hook member as the latter is moved an arcwise motion. At 11 is pivoted the rod 12 which at its opposite end is pivoted to the bell crank lever 13 at 14. Said lever is adapted to be grasped by the 50 operator and swung on its pivot 15 to engage or release the locking hook member 7.

Assuming the door 4 to be in its closed position and locked as shown in the figure, to open the door the operator grasps the

lever 13 and draws it downwardly thereby 55 swinging the end of the rod at 14 in an arc, which will result in imparting a longitudinal movement to the rod after the pivotal point 14 has passed below the horizontal plane of the pivotal point 15, thereby thrusting 60 the hook member 7 rearwardly on its supporting bar 9, and the latter will also impart an arcwise movement to the hook member as the manipulation of the rod 12 continues. The rotary movement induced in 65 the hook member by the thrust of the rod 12 tends constantly to bring the hook member to an unlocking position, but this complete unlocking is counteracted for a little time by the swinging of the supporting 70 member or bar 9 which tends to bring the hook member to a lower position. The result of the construction and manipulation is to thrust the hook away from contact with the door permitting the door to swing open 75 a little to permit a discharge of the lading in small quantity as desired and upon a further manipulation of the lever 13 the hook member may be entirely released from the door and the lading then is free to pour 80 forth in mass. The door may be maintained in this position just short of being unlocked so long as the operator wishes, the advantage being that the lading may be spread or 85 strewn instead of being dumped, or both practices may be resorted to at will.

It will be noted that the rod 12 is suspended from its ends at its pivotal connections and that its entire movement is such only as is imparted to it positively by the 90 lever 13.

When the door is swung back to closed position as the car body is righted, the hook member is drawn into engagement therewith by the rotation of the lever 13 back to 95 its position illustrated in the heavy lines in the drawing. The quadrant 16 secured to the front end of the body may be provided with notches or other stop means for the lever which will enable the operator to lock 100 the lever 13 in any position desired.

What we claim as new is:—

In a vehicle having a body adapted for the reception of lading and the discharge of said lading through one end thereof, a door 105 for said body pivotally suspended from its upper edge to permit the discharge of lading and to effect the closure of the discharge

opening, a bar member pivotally mounted on said body adjacent said door, a hook member pivotally mounted on said bar member for arcwise movement, an operating rod 5 extending along said body pivotally connected with said hook member, and manipulating means associated with the opposite end of said rod adapted to urge said hook member rearwardly to permit the opening

of said door and to retract said hook member 10 to effect the closing of said door.

In testimony whereof we affix our signatures in the presence of two witnesses.

WILLIAM L. BURNER.
JAMES H. COTTON.
